UNITED STATES PATENT OFFICE.

HERBERT G. UNDERWOOD, OF NEW YORK, N. Y.

INTERNAL-COMBUSTION ENGINE.

No. 846,434.

Specification of Letters Patent.

Patented March 5, 1907.

Original application filed June 7, 1905, Serial No. 264,042. Divided and this application filed October 25, 1905. Serial No. 284,270.

To all whom it may concern:

Be it known that I, HERBERT G. UNDERWOOD, a citizen of the United States, residing at New Brighton, borough of Richmond, city of New York, State of New York; have invented certain new and useful Improvements in Internal-Combustion Engines, of which the following is a specification, reference being had to the accompanying drawing, forming a part hereof, this application being a division of application Serial No. 264,042, filed June 7, 1905.

This invention relates particularly to the means for controlling the charge or fuel mixture of air and gas or vapor for internal-combustion engines and for regulating the admission of the charge to the working cylinder.

The invention will be more fully explained hereinafter with reference to the accompanying drawings, in which it is illustrated as embodied in a convenient and practical form.

In said drawings, Figure 1 is a front elevation of an internal-combustion engine to which the present improvement is applied. Fig. 2 is a view of the upper portion thereof in side elevation. Fig. 3 is a view in vertical section of the upper portion thereof on the plane indicated by the line 3 3 of Fig. 2. Fig. 4 is a detail view in section on the horizontal plane indicated by the line 4 4 of Fig. 1. Fig. 5 is a detail view, on an enlarged scale, of a portion of the governor mechanism.

In the engine represented in the drawings the working cylinder *a* is suitably supported by struts *b* upon a base-plate *b'*, to which are secured the bearings for the crank-shaft *e*, the cylinder-head being at that end of the cylinder which is nearest to the crank-shaft *c*. The cranks *c'* are connected by pitmen *c* with studs *d*, which project from the upwardly-extended cylindrical trunk-piston *d'* through slots *a'* in the upward extension *a'* of the cylinder *a*. As will be observed by reference to Fig. 3, the trunk-piston *d'* when in its highest position extends nearly to the head *a''* of the cylinder extension *a'*, its length being greater than its stroke, so that the slots *a'* in the cylinder-wall are always covered by the trunk-piston. The piston *d'* is provided near its forward or head end with a port *d''*, which is adapted to register as the piston approaches the limit of its forward stroke with a port *a''* in the cylinder-wall. The latter communicates with a chamber *a''*, in which the air is mixed with the fuel basis

of the explosive charge, and the latter communicates with the head end of the cylinder—that is, with the working cylinder—through a port *a''*, which is likewise uncovered by the piston as it approaches the limit of its upward or forward stroke. An exhaust-port *a''* is also provided in the wall of the working cylinder to be uncovered by the piston as it approaches the limit of its forward stroke. In the wall of the cylinder extension *a'* are also provided air-inlet ports *a''* in such position as to be uncovered by the piston as the latter approaches the limit of its downward or rearward stroke. With this construction the air admitted through the ports *a''* is compressed during the forward movement of the piston and is admitted to the working cylinder as the piston completes its forward stroke.

The fuel basis of the explosive mixture is supplied from any suitable source through a pipe *h*, which is provided with a nozzle and valve-chamber *h'* within the mixing-chamber *a''*. The extremity of the pipe is provided with an inwardly-opening valve *h''*, which is held normally to its seat by a spring *h''*. The stem of the valve *h''* projects beyond the extremity of the pipe *h'* into the path of an arm *i*, by which the valve is opened to permit the escape of the proper quantity of fluid to form the basis of the explosive mixture. The arm *i* is secured to a shaft *i'*, which is extended through the wall of the mixing-chamber *a''* and is provided exteriorly with an arm *i''*, adapted to be acted upon by some moving part of the engine to open the valve *h''* at the proper instant. In the engine shown the valve is operated by a mechanism which is dependent upon the speed of the engine or, in other words, by governor devices. As shown particularly in Figs. 1 and 2, an arm *k*, pivoted, as at *k'*, upon a suitable bracket, is connected by a link *k''* with one of the pitmen *c*, so that it is swung up and down as the piston reciprocates. Upon the lever *k*, which constitutes a vibrating carrier therefore, is pivoted a pendulum-arm *l*, which is pressed normally in one direction by a spring *k''*, adjustably supported through a screw *k''* upon an arm *k''* of the lever *k*. The pendulum is provided with a finger *l'*, which in the normal operation of the engine overlies the extension of the arm *i''* on the shaft *i'*, so that as the lever *k* is swung up and down the shaft *i'* is oscillated and the valve *h''* is opened at every downward movement of the lever. If

however, the engine is operating at a speed higher than the normal, then the pendulum-arm l assumes such a position relative to the shaft i' that the finger l' thereof fails to engage the arm i^2 and the valve h^2 therefore is not opened to admit more fluid.

It may be desirable not only to prevent the admission of fuel when the engine is running too fast, but to prevent also the admission to the working cylinder of whatever mixture there may be in the mixing-chamber a^5 and even of additional air. For this purpose there is provided a butterfly-valve m , mounted within the mixing-chamber a^5 upon a shaft m' , which carries outside of the mixing-chamber a triangular block m^2 . A flat spring m^3 is secured to the supporting-bracket to co-operate with the block m^2 and maintain the valve in one position or the other, as the case may be. The block m^2 is also provided with lugs m^4 and m^5 , which are arranged to coöperate with a finger l^2 , also carried by the pendulum l . Normally the valve m stands in the position represented in full lines in Figs. 3 and 5, leaving the passage unobstructed; but if the engine runs too fast and the admission of fuel is cut off by the action of the pendulum l then at the same time the finger l^2 of the pendulum swings into position to strike the lug m^5 on the block m^2 , rocking the shaft and the valve m into the position of the latter, (indicated by dotted lines,) in which it pre-

vents the passage of air or vapor through the mixing-chamber. As soon as the engine resumes normal speed then the finger l^2 strikes the lug m^4 of the block m^2 and restores the valve to its operative position.

It will be understood that various changes may be made in the details of construction and arrangement of parts and that the invention is not to be limited to the precise construction and arrangement shown and described herein.

I claim as my invention—

In an internal-combustion engine, the combination of a working cylinder, an air-compressor connected to said cylinder, a mixing-chamber included in said connection, means to supply the fuel basis of the charge to said chamber, a valve to control the passage from said chamber to said cylinder, a valve-stem carrying two projections, a vibrating carrier, a pendulum mounted on said carrier and adapted to engage one or the other of said projections to shift the valve and means to retain the valve in either position, substantially as described.

This specification signed and witnessed this 24th day of October, 1905.

HERBERT G. UNDERWOOD.
